LAMP BASE

Arthur Schalamon, Cleveland, Ohio

Application December 30, 1949, Serial No. 6,924

Term of patent 7 years

(Cl. D48—20)

To all whom it may concern:

Be it known that I, Arthur Schalamon, a citizen of the United States, residing at Cleveland, State of Ohio, have invented a new, original, and ornamental Design for a Lamp Base, of which the following is a specification, reference being had to the accompanying drawing, forming a part hereof, in which:

Fig. 1 is a front elevational view of a lamp base, showing my new design.

Fig. 2 is a side elevational view of Fig. 1.

Fig. 3 is an opposite side elevational view of Fig. 1.

Fig. 4 is a rear elevational view of Fig. 1.

Fig. 5 is a cross sectional view taken on a horizontal line 5—5 through Fig. 1 at a point slightly above the base and looking downward.

The dotted lines shown in the drawing are for illustrative purposes only.

I claim:

The ornamental design for a lamp base, as shown and described.

ARTHUR SCHALAMON.
